United States Patent Office

Des. 177,862
Patented May 29, 1956

177,862

TEAMAKER OR SIMILAR ARTICLE

Peter Schlumbohm, New York, N. Y.

Application June 27, 1955, Serial No. 36,710

Term of patent 14 years

(Cl. D44—26)

FIG. 1.

FIG. 2.

FIG. 3.

Fig. 1 is a side view of a teamaker showing my new design;

Fig. 2 is an end view thereof, the device being rotated 90 degrees from the position of Fig. 1; and

Fig. 3 is a top plan view thereof.

I claim:

The ornamental design for teamaker or similar article, as shown.
